MACHINE TO BAND BUNDLES

John Douglas Robertson, Taunton, Mass.

Application August 10, 1938, Serial No. 224,048

22 Claims. (Cl. 93—93)

This invention relates to a machine to apply bands to bundles.

My principal object is to provide a machine that will supply a predetermined length of band material for a bundle, and after the band is wrapped around the bundle in the form of a loop, in response to a single movement of the operator, will join two portions of the band together making a flat joint in the loop itself, then sever the main supply of the band material therefrom, and automatically present a said predetermined length of the band material to wrap the next bundle with. Another object is to provide such a machine to do this wrapping with a band made of material that presents a uniformly good appearance, that is strong, with the minimum use of labor and time; and, when embodying one form of joining means, does not involve any expense for adhesive or staples. A further object is to make it possible for the operator to simply pull out some extra band material in addition to the predetermined length from the supply whenever the size of the bundle so requires.

The foregoing and other objects which will appear as the nature of the invention is better understood, may be accomplished by a construction, combination and operative arrangement of parts such as is disclosed by the drawings and specification. The nature of the invention is such as to render it susceptible to various changes and modifications, and, therefore, I am not to be limited to said disclosure; but am entitled to all such changes therefrom as fall within the scope of my claims.

In the drawings:

Figure 1 is a side elevational view with a side frame removed, of a banding machine embodying my invention.

Figure 2 is a plan view thereof.

Figure 3 is an enlarged and elevational view of the same.

Figure 4 is a side elevational view of the pedal operating mechanism and its connections.

Figure 5 is an enlarged perspective view of one of the crimping dies.

Figure 6 is a sectional view taken on the line 6—6 of Figure 2.

Figure 7 is a sectional view taken on the line 7—7 of Figure 2.

Figure 8 is a diagrammatic sectional view illustrating the band feeding and cutting members.

Figure 9 is a diagrammatic sectional view showing my machine equipped with a stapling device.

Figure 10 is a sectional view taken on the line 10—10 of Figure 9.

Figure 11 is a perspective view of a band alone formed on a machine embodying that form of my invention which makes use of staples to join the ends of the band.

Figure 12 is a perspective view of a band only formed on a machine embodying that form of my invention in which the ends of the band are joined by crimping them together under heavy pressure.

Figure 13 is a perspective view of a bundle banded on a machine embodying my invention.

As illustrated, the side frames of the machine 15 preferably mounted on table, bench, or counter, are represented by the numerals 1 and 2 which are tied together by spacers 3 secured by screws 4. Between the rear portions of the side frames is located a supply roll 5 of tape made of paper or other suitable material either plain or printed. This roll of tape is located laterally between approximately semi-circular plates 6 and 7 which are adjustably carried by clips 8 on said spacers 3. To facilitate the adjustment of 20 these plates each one is provided with two laterally movable handles 77 connecting with plates 6 and 7 projecting through side frames 1 and 2. In order to provide an unbroken surface on the plates 6 and 7 next to the roll 5 the metal of 25 the plates is cut and bent as shown at 6a and 7a to form a detachable connection with the handles 77. It will be noted that the handles are graduated to indicate the proper setting for the width of tape being used. The roll 5 of tape 30 rests on rolls 9 which are journaled in the side frames 1 and 2. A cover 57 is provided over the tape roll and tape feeding part of the mechanism shown hinged at 59. Stop 60 retains it in open position.

The band or strip of tape 10 is drawn from supply roll 5 through tape guides 11 and 12 by 35 means of feed rolls 13 and 14. Guides 11 and 12, shown as made of sheet metal bent U-shaped in cross section with the closed ends of the U's toward the inner surfaces of the side frames, are adjustably mounted by means of friction spring clips 14A riveted to them and supported and frictionally located on two spacers 3. The 40 guides 11 and 12 extend forwardly past rotatable feed rolls 13 and 14 to within a small clearance of knife 21. To facilitate the adjustment of guides 11 and 12 graduated handles 77a are provided similar to those shown and described for adjustment of plates 6 and 7 and similarly 45 mounted.

The drive feed roll 14 is carried on a shaft 15 preferably journaled in ball bearings 15A, the outer races of which are mounted in fixed position on the side frames 1 and 2. The drive feed roll 14 is preferably provided with a rubber surface for frictional driving contact with the tape 10. Feed roll 13 is carried on a shaft 16 preferably journaled in ball bearings 16A, the outer races of which are mounted on side frames 1 and 2 in vertical slots 17 and 18 so as to be movable vertically. The ball bearings 16A are pressed vertically downward by suitable springs 19 so the tape will be nipped between rolls 13 and 14 with sufficient force to feed the tape but capable of yielding sufficiently to permit the operator to raise roll 13 away from roll 14 enough to insert the tape when threading the machine. Said springs 19 are so formed to provide a stop portion 19a and a bend 19b. Said bends 19b force said ball bearings 16a downwardly when the said rolls 13 and 14 are in contact, as shown in Figure 1 of the drawings. When said rolls are separated to insert band material said bends 19b hold them separated by forcing ball bearings 16a upwardly against said stop 19a.

Drive feed roll 14 on its shaft 15 is rotated preferably by gear teeth 22 cut into the shaft 15 in mesh with gear 23 rotatably mounted on fixed spacer 24. Also rotatably mounted on spacer rod 24 beside gear 23 is sprocket 25 on the hub of which are cut ratchet teeth 26. Sprocket 25 and gear 23 are located laterally between the shoulder 26A of spacer 24 and boss 27 of side frame 1. Gear 23 is rotated by pawl 28 mounted on stud 29 fixed to gear 23 pressed into engagement with ratchet teeth 26 of sprocket 25 by ratchet spring 30.

Sprocket 25 is rotated by chain 31 which is pulled by tension spring 32 which is anchored to spacer rod 33 fixed to the side frames 1 and 2. Chain 31 extends from spring 32 part way around sprocket 25 downwardly to the upper end of a rod 62 which is the upper rod of a turnbuckle 63, the lower rod 64 of which is pivotably attached by pin 67 to a slide 65 mounted on a lever 34 shown pivoted on a floor bracket 34A at a pin 34B. This slide 65 may be slid along lever 34 to alter its distance from the lever fulcrum pin 34B in floor bracket 34A. Slide 65 is provided with a clamping screw 66 to hold it set in the desired position on the lever 34, and an index 66A to indicate its position relative to the scale 66B is provided on the slide 65. Scale 66B is numbered preferably to indicate the length of tape feed in inches resulting from its position.

Lever 34 is connected to and operated by a pin 71 projecting from a pedal lever 72 opposite a boss 73 engaging a slot 74 in lever 34. Lever 72 is fulcrumed in floor bracket 75 at pin 76. Lever 72 is formed into a foot pedal at 58 at one end. This double lever arrangement is used to increase the angular movement of lever 34, carrying said slide 65 in response to a given amount of movement applied to pedal 58. Of course, this object could be attained by other means, such as a single lever, in which event the operating force would be applied directly to the lever carrying the slide 65.

To present tape 10 at a point for wrapping around a bundle it is fed through guides 11 and 12 by feed rolls 13 and 14 thence between and beyond fixed cutting knife 21 and swinging cutting knife 21A. Fixed cutting knife 21 is located above the path of the tape and extends transversely of

said path with its cutting edge in the plane of its surface farther from the feed rolls 13 and 14. Knife 21 is shown attached by screws 35 to cross frame 36 which in turn is attached to side frames 1 and 2 by screws 37.

Swinging knife 21A is located below the path of the tape being fastened to swinging knife holder 38 by screws 39. Swinging knife 21A has its cutting edge in the plane of its surface nearest to the feed rolls 13 and 14 to cooperate with the cutting edge of the fixed knife 21. Swinging knife holder 38 is pivoted on stud 40 threaded into cross frame 36. The swinging knife holder is provided with a spring 41 to hold the cutting edge side of the swinging knife 21A close against the cutting edge side of the fixed knife 21. Swinging knife 21A is provided with an upwardly projecting portion 42 extending from the end of the knife 21A at a point between the path of the tape 10 and the fulcrum pin 40. This projection 42 extends upwardly far enough to overlap knife 21 even when knife 21A is at its lowest position, thus preventing swinging knife 21A from being forced into interference with fixed knife 21 by the action of the spring 41. Said spring 41 is attached at one end to the swinging knife holder 38 by screws 43 tapped into the side of the holder 38, and at its other end it engages a slot in holder 38. The middle portion of spring 41 presses against the outer surface of screw 40.

The end of the swinging knife holder 38 furthest removed from the knife is formed as shown in Figure 3 to engage and be operated by the projecting end of pin 44 when pin 44 approaches the bottom of its stroke. The different positions of said pin 44 during the cutting operation are indicated by dot and dash lines in said Figure 3.

Tape 10 is fed between the fixed and swinging cutting knives preferably to the extent needed to give the length of tape necessary to reach around the bundle being banded and to overlap on itself as at 10a at the tape crimping device or stapling device, later described.

The tape crimping device consists of two pairs of hardened and polished steel crimping dies, each pair comprising one fixed die 45 and one movable die 45a. The fixed dies are located above the path of the tape and are recessed into cross frame 36 and secured therein by upsetting the metal of cross frame 36 around them. The construction of these dies including their serrations 45b in the contacting surfaces is shown in large scale view in Figure 5 of the drawings.

The movable dies 45a are located below the path of the tape and are recessed into equalizer 46 and secured thereto by upsetting the metal of the equalizer 46 around them. Equalizer 46 is semi-circular in shape to match a similarly shaped recess in a crimping lever 47. Crimping lever 47 is pivoted on axle 48 carried in holes in the dependent sides of cross frame 36. Attached to crimping lever 47 near its crimping die end and extending downward from it is spring 48A with its lower end secured to side frame 2. At 69 is an open ended slot in side frame 36 through which the tape is fed and from which the completed band is removed. The end of crimping lever 47 opposite from the crimping die end is forked and carries on an axle 49 the four-sided cam member 50. Recessed into cross frame 36 immediately above cam member 50 is steel plate 50A and rubber disk 50B located so as to take the reaction of cam 50. Pivoted on

the projections of axle 49 extending beyond the sides of crimping lever 47 is the bent forked lever 51. Lever 51 carries pin 52 on which is pawl 53 spring pressed by spring 54 against the ratchet notches cut in the edge of cam member 50.

The end of lever 51 opposite from the cam end carries projecting pin 44 in a hole drilled through it. Also carried by this pin 44 is the clevis 55 into which is screwed rod 56 supplied with turnbuckle 78 connected in turn with rod 79. The lower end of rod 79 is looped around stud 80 which is screwed into strap 81. Strap 81 is attached by screws 82 to lever 34.

As previously stated the rear end of lever 34 is fulcrumed on floor bracket 34A. The longitudinal center line of lever 34 is approximately horizontal and is located vertically below sprocket 25 in the plane through the middle of the width of the sprocket 25. Spring 32 acting through chain 31 normally holds lever 34 up against pedal lever stop 61.

Surrounding the three sides of the cross frame 36 other than the feed mechanism side is shelf 68 located with its upper surface just a trifle below the lower edge of slot 69 in cross frame 36. The tape 10 is fed across this shelf 68 and the bundle to be banded is placed upon the tape 10.

The operator passes the tape around the bundle and introduces the end of the tape into the crimping mechanism by the help of the deflector 70 which is attached to cross frame 36 by screws 35.

Having described an illustrative construction of the mechanism embodying my invention the sequence and manner of operation will now be described.

To put the machine into operation cover 57 is hinged open at point 59 and retained so by stop 60. Upper feed roll 13 is lifted out of engagement with roll 14 in which position it is held by spring 19.

Several inches of the end of the tape 10 is unrolled from roll 5 and inserted within the guides 11 and 12 an inch or two beyond the near edge of shelf 68, swinging knife 21A being normally below the path of the tape 10. The printed side is down if printed tape is used so as to cause the printed side of the band to be visible when it surrounds the bundle. The roll of tape 5 is next put in place against the rolls 9 and located laterally midway between side frames 1 and 2 by slidably adjusting plates 6 and 7 and their attached clips 8 frictionally engaging the spacers 3 by means of handles 71.

Guides 11 and 12 and their attached spring friction clips 14A are slidably adjusted on spacers 3, by means of handles 71A, to guide tape 10 midway of the side frames 1 and 2 to line up with roll 5. Roll 13 is pushed downward into operating position to allow its spring 19 to press it against roll 14.

Next slide 65 is adjusted on lever 34 so that its index is opposite the number on the scale on lever 34 that indicates the number of inches of tape desired for the band to be made, and it is clamped in this position by clamp screw 66. To cut the tape 10 back to a point opposite knives 21 and 21a, so that a correct start may be made, the pedal 58 is depressed by the operator's foot from its normal or upmost position to cause the swinging knife 21A to cut off the small end 10b of the tape which in threading up had been inserted slightly beyond the near edge of shelf 68.

This motion of swinging knife 21A results from depressing pedal 58 because pedal lever 72 carrying pin 71 is activated thereby. Pin 71 engaging slot 74 in lever 34 in turn depresses lever 34. Attached to lever 34 by screws 82 is strap 81 carrying stud 80 around which is looped the lower end of rod 79. As lever 34 is depressed rod 79 follows carrying turnbuckle 78, into the upper end of which is screwed the lower end of rod 56. As rod 56 drops it carries with it clevis 55 which is screwed onto its upper end. Clevis 55 is pivotably connected to lever 51 by means of pin 44 projecting into the path of the swinging knife holder 38. As clevis 55 drops pin 44 strikes swinging knife holder 38 near the end of its stroke and causes swinging knife 21A to raise past fixed knife 21 and cut the tape.

The operator now removes her foot from pedal 58 thus permitting spring 32 to contract in length pulling with it chain 31. The movement of chain 31 rotates sprocket 25 carrying ratchet teeth 26 on its hub. Pawl 28 engaging ratchet teeth 26 and pivoted on stud 29 in turn rotates gear 23 to which stud 29 is secured. Gear 23 meshing with teeth 22 cut into shaft 15 of drive feed roll 14, causes feed roll 14 to rotate and deliver the required length of banding material across shelf 68.

The machine is now ready for use.

The operator places a bundle on the tape, picks up the end of the tape, passes it around the bundle and inserts the end of the tape between the deflector 70 and the cross frame 36 between the two pairs of crimping dies 45 and 45a about an inch or slightly more than the length of the crimping dies.

Pedal 58 is now depressed carrying with it pedal 72 and, by means of pin 71, lever 34. As previously described, lever 34 thru rods 79 and 56, clevis 55 and pin 44 rotates lever 51. As lever 51 swings it carries attached to it stud 52 supporting pawl 53. Pawl 53 in turn engages ratchet teeth cut in cam 50 and causes it to turn.

Cam 50 is pivoted on pin 49 carried by crimping lever 47. The tension spring 48A attached to crimping lever 47 holds cam 50 against steel plate 50A. Steel plate 50A is backed up by a rubber disk 50B which acts as a compression spring. As one of the high spots on cam 50 is brought into contact with plate 50A by the rotation of cam 50 the cam center is forced away from plate 50A carrying its end of crimping lever 47 with it. This forces the opposite end of lever 47 upward carrying with it equalizer 46 and the movable dies 45a. The two thicknesses of the band material are thus squeezed between the fixed and movable dies. The dies are so shaped that the fibres of one thickness of band material are forced into such intimate contact with the fibres of the other thickness of band material, and the material is so locked together by the changing of shape of the small pieces between the serrations of the dies, that the two thicknesses of material are joined together much as a tinsmith locks two pieces of sheet metal.

When thick banding material is used rubber disk 50B is compressed more than when thin banding material is used, thus acting as a safety device to avoid development of excessive pressure at the dies with resulting weakening of the joint and to avoid excessive strain with permanent distortion of the parts.

It will be observed that the parts are so de-

signed and related that the crimping dies 45 and 45A are separated when pedal 58 is held in normal position at the top of its stroke by spring 32, and are forced tightly together approximately at the middle of its stroke and are again widely separated at the end or completion of its stroke in one direction. Of course, this result could be attained by using a cam with a different number of lobes than the number shown and changing the angle of oscillation of lever 51 to maintain it at a little more than 360 degrees divided by the number of lobes on the cam.

When lever 51 is rotated by depressing pedal 58, as described above, pin 44, carried by lever 51 strikes moving knife holder 38 near the end of the stroke of said pin and moves said holder 38 downwardly to the end of its stroke thus forcing the opposite end of holder 38 upwardly, thereby carrying moving knife 21A past fixed knife 21 and separating the band B so formed from the roll of banding material.

Holding her foot on pedal 58 to keep the crimping dies separated the operator removes the bundle with its band on it from the machine by sliding it sidewise on the shelf 68 while the band slides out of the slot 69.

Removing her foot now from pedal 58 the same length of band material is again fed across table 68 ready for the next bundle to be placed on it.

In Figure 9 of the drawings I show the movable part of a well known stapling device S which is used in place of said crimping dies, being pivoted at 85 to said table 68, and operated while in an inverted position, as shown. Said shelf 68 is provided with an opening 68a, immediately above which is an anvil 86 secured by screws 87 to said table 68. Said lever 47 when operated as previously described actuates a plunger 88 of said stapling device S opposite said opening 68a to thereby drive a staple 90 through the overlapping portions 10a of said band material 10.

Should more than the predetermined length of band material 10 be needed the operator may pull out the extra material needed because pawl 28 will click over ratchet teeth 26 permitting the feed rolls 13 and 14 to turn even though sprocket 25 remains stationary.

What I claim is:

1. A machine of the class described comprising operable means to feed fibrous band material, operable means adapted to distort and thereby interjoin two portions of said band material, operable means spaced from and independent of said joining means to sever said band material between said joined portions and the remainder of said material, and operable mechanism connected to and adapted upon actuation to actuate said feeding means, joining means and severing means.

2. A machine of the class described comprising operable means to feed fibrous band material such as paper or cardboard, operable means adapted to join two portions of said band material together that are overlapped, operable means to sever said band material between said joined portions and the remainder of said material spaced laterally from the point where said portions overlap towards said feed means and mechanism operably connected to said feeding means, joining means and severing means having movable lever means operatively connected to said joining means, feeding means and severing means

embodying connecting parts which are adapted to be actuated by an independent movement and thereby operate said joining means, severing means and feeding means progressively in the order named.

3. A machine of the class described comprising operable means to feed band material, operable means to join two portions of said band material together, operable means to sever said band material between said joined portions and the remainder of said band material, and operable mechanism connected to and adapted upon actuation to actuate said feeding means, joining means and cutting means embodying movable lever means adapted upon actuation to operate said mechanism, and movable adjustable means connected with said mechanism embodying a slide movably connected with said lever means and adapted to limit the movement of said operable mechanism that actuates said feeding means and thereby determine the length of said band material to be fed when said mechanism is actuated.

4. A machine of the class described comprising operable means to feed band material, operable means to join two portions of said band material together embodying a movable member, operable means to sever said band material between said joined portions and the remainder of said material embodying a movable cutting member that is in substantially the same horizontal plane during the severing operation as said joining means movable member is during the joining operation, and operable mechanism connected to and adapted upon actuation to actuate said joining means, operable means connected to said severing means and to said operable mechanism adapted to be actuated by said mechanism after said joining means has been actuated to thereby actuate said severing means, and operable instrumentalities connected to said feed means and to said operable mechanism adapted to be actuated by said mechanism after said severing means has been actuated to thereby actuate said feed means.

5. A machine of the class described comprising operable means to feed band material, operable means to join two portions of said band material together in an endless loop, said joining means being so positioned with relation to said two portions of said band material as to join said portions in the said loop itself, operable means to sever said band material between said joined portions and the remainder of said material, and operable mechanism connected to and adapted to actuate said joining means having a movable lever adapted to move in a positive stroke and return and to actuate said joining means on its positive stroke, operable means connected to said severing means and to said operable mechanism adapted to be actuated by said positive stroke of said lever to thereby actuate said severing means, and operable instrumentalities connected to said feed means and to said operable mechanism adapted to be actuated upon said return stroke of said lever to thereby actuate said feed means.

6. A machine of the class described comprising operable means to feed band material, operable means to join two portions of said band material together, operable means to sever said band material between said joined portions and the remainder of said material, and mechanism operably connected to and adapted upon actuation to actuate said feeding means, joining means and

severing means, said joining means embodying two members adapted to coact with each other to thereby join said portions together, said severing means embodying two cutting blades adapted to coact with each other, said mechanism embodying a cam, and a movable lever adapted to directly receive the primary operating impulse operably connected thereto adapted when actuated to move in one direction and return, and adapted in its first movement to actuate said cam and mechanism to cause one said joining member to move towards the other and afterwards during said first movement to cause said moved joining member to move away from the said other.

7. A machine of the class described comprising operable means to feed band material, operable means to join two portions of said band material together, operable means to sever said band material between said joined portions and the remainder of said material, and mechanism operably connected to and adapted upon actuation to actuate said feeding means, joining means and severing means, said joining means embodying two members adapted to coact with each other to thereby join said portions together, said severing means embodying two cutting blades adapted to coact with each other, said feeding means embodying two roll members adapted to coact with each other, said mechanism embodying a movable lever adapted when actuated by the operator to move in one direction and return and adapted in its first movement to move one said joining member towards the other and adapted during said first movement to thereafter move said joining member away from the said other, said mechanism embodying a movable chain and a tension spring connected thereto and adapted to be pulled by movement of said chain, said chain and spring being movably connected to a said feed roll and to said lever and adapted upon said return movement to cause said feed roll to rotate to thereby deliver a supply of said band material for use.

8. A machine of the class described, comprising operable means to feed band material, operable means to join two portions of said band material together in an endless loop, operable means to sever said band material between said joined portions and the remainder of said material, mechanism operably connected to and adapted upon actuation to actuate said feeding means, joining means and severing means, and means to support a bundle to be banded directly above said joining means, said joining means embodying stapling means, all of said severing means being spaced rearwardly of that portion of said supporting means that is adapted to support a bundle, and part of said severing means being higher than said supporting means portion.

9. A machine of the class described comprising operable means to feed band material having a feed roll member, operable means to join two portions of said band material together, operable means to sever said band material between said joined portions and the remainder of said material, and operable mechanism connected to and adapted upon actuation to actuate said feeding means, joining means and severing means, said mechanism embodying movable lever means adapted to be actuated by the operator of said machine, a slide member movably mounted on said lever means and connected with said mechanism, means operably connected with said feed roll and said lever means whereby actuation of

5 said lever means actuates said feed roll to deliver a portion of said band material for use in wrapping around a bundle, the length of which is determined by the position of said slide member on said lever means.

10. A machine of the class described comprising operable means to feed band material, operable means to join two portions of said band material together, operable means to sever said band material between said joined portions and the remainder of said material having a movable knife member and holder therefor, and operable mechanism connected to and adapted upon actuation to actuate said feeding means, joining means and severing means, said mechanism embodying a movable lever adapted to be actuated by the operator of said machine, another movable lever connected to said first lever, a movable rod connected to said second lever, a third movable lever carrying a pin projecting therefrom, said knife member holder and pin being in the same path of movement whereby upon contactual movement of said pin and said knife member the latter is actuated to cutting position to thereby sever said tape.

11. A machine of the class described comprising operable means to feed band material, operable means to join two portions of said band material together, operable means to sever said band material between said joined portions and the remainder of said material having a movable knife member and holder therefor, and operable mechanism connected to and adapted upon actuation to actuate said feeding means, joining means and severing means, said mechanism embodying a movable lever adapted to be actuated by the operator of said machine, connecting means operably connected to said lever, a pin carried by and projecting from said connecting means, said knife member holder and pin being in the same path of movement and normally spaced from each other and so positioned that movement of said pin in said path to a predetermined point brings it into contact with said knife holder thereby actuating said knife member to cutting position.

12. A machine of the class described comprising operable means to feed band material having a feed roll, operable means to join two portions of said band material together, operable means to sever said band material between said joined portions and the remainder of said material having a movable knife member and holder therefor, and operable mechanism connected to and adapted upon actuation to actuate said feeding means, joining means and severing means, said mechanism embodying movable lever means adapted to be actuated by the operator of said machine, a movable rod connected to said lever means, a clevis connected to said rod, another movable lever, a pin carried by said other movable lever and operably connecting said other movable lever to said clevis, said knife member holder and pin being in the same path of movement whereby upon contact with each other said knife member is actuated to cutting position to thereby sever said tape, a spring normally holding said lever means in a predetermined position, and adapted to be actuated by movement of said lever means, means adapted to be actuated by contraction of said spring operably connecting said spring and said feed roll whereby said feed roll is adapted to deliver a portion of said band material for use in wrapping around a bundle.

13. A machine of the class described, comprising means to guide band material as it is drawn into position for use, means to support a bundle to be banded, operable means to join two portions of said band material together in an endless loop while said bundle is supported by said supporting means embodying a movable member and a fixed member adapted to coat therewith, operable means to sever said band material between said joined portions and the remainder of said material, said fixed member being so positioned as to also provide support for a bundle to be banded directly above said movable member, mechanism operably connected to and adapted upon actuation to actuate said joining means and severing means, said severing means being rearwardly of said movable and fixed members and spaced laterally from the portion of said supporting means that is adapted to support said bundle, and being adapted to be actuated by said mechanism after the joining operation has been performed.

14. A machine of the class described comprising operable means to feed fibrous band material, operable means to join two portions of said band material together embodying a member normally above said material and a member normally below said material, operable means independent of and spaced from said joining means to sever said band material between said joined portions and the remainder of said material embodying a severing member above said material and a severing member below said material, operable mechanism connected to and adapted upon actuation to actuate said feeding means, joining means and severing means, and a deflector positioned laterally adjacent said joining means above said material and extending to a point adjacent said severing member that is above said material, said deflector extending away from said joining means towards said latter-mentioned severing member upwardly and outwardly whereby the space between said joining means and said deflector increases from the bottom of said deflector upwardly.

15. A machine of the class described comprising operable means to feed fibrous band material, operable means adapted to distort and thereby interjoin two portions of said band material, operable means spaced from and independent of said joining means to sever said band material between said joined portions and the remainder of said material, and operable mechanism connected to and adapted upon actuation to actuate said feeding means, joining means and severing means, said mechanism embodying instrumentalities adapted to directly effect actuation of said severing means and other instrumentalities adapted to directly effect actuation of said joining means.

16. A machine of the class described comprising operable means to feed fibrous band material, operable means adapted to distort and thereby interjoin two portions of said band material, operable means movable independently of said joining means to sever said band material between said joined portions and the remainder of said material, and operable mechanism connected to and adapted upon actuation to actuate said feeding means, joining means and severing means, said mechanism embodying instrumentalities adapted to cause actuation of said severing means and other instrumentalities adapted to cause actuation of said joining means.

17. A machine of the class described comprising operable means to feed fibrous band material, operable means adapted to distort and thereby interjoin two portions of said band material, operable means movable independently of said joining means to sever said band material between said joined portions and the remainder of said material, and operable mechanism connected to and adapted upon actuation to actuate said feeding means, joining means and severing means, said mechanism embodying instrumentalities adapted upon actuation of said mechanism to directly cause actuation of said severing means and other instrumentalities adapted upon actuation of said mechanism to directly cause actuation of said joining means, said mechanism embodying parts so operably connected that said joining means is operated before said severing means severs said material.

18. A machine of the class described comprising operable means to feed fibrous band material, operable means adapted to distort and thereby interjoin two portions of said band material, operable knife means spaced from and movable independently of said joining means to sever said band material between said joined portions and the remainder of said material, said knife means embodying a movable knife and holding means therefor, and operable mechanism connected to and adapted upon actuation to actuate said feeding means, joining means and knife means, said mechanism embodying instrumentalities adapted to directly cause actuation of said holding means and other instrumentalities adapted to directly cause actuation of said joining means.

19. A machine of the class described comprising operable means to feed fibrous band material, operable means adapted to distort and thereby interjoin two portions of said band material embodying two mating dies having spaced serrations therein, said dies being so operably positioned that the serrations in one die are opposite the spaces between the serrations in the other die, operable means to sever said band material between said joined portions and the remainder of said material, and operable mechanism connected to and adapted upon actuation to actuate said feeding means, joining means and severing means to thereby cause the said serrations in one said die to enter said spaces in the other said die.

20. A machine of the class described comprising operable means to feed fibrous band material, operable means adapted to distort and thereby interjoin two portions of said band material embodying a pair of V-shaped tooth members so positioned that the apexes of said V-shaped tooth members are opposite the spaces between the apexes of the other V-shaped tooth members, operable means to sever said band material between said joined portions and the remainder of said material, and operable mechanism connected to and adapted upon actuation to actuate said feeding means, joining means and severing means to thereby cause the teeth of a said V-shaped tooth member to enter the spaces between the apexes of the other V-shaped tooth member.

21. A machine of the class described comprising operable means to press together and interjoin two portions of band material embodying a movable member, operable means embodying a stationary member to cut said band material

between said joined portion and the remainder of said band material, operable mechanism connected to and adapted upon actuation to actuate said joining means and cutting means, means to hold a supply of materials, and means to guide the leading edge of said material to cause it to be presented to said joining and severing means, said guiding means being attached to said stationary member, and means to support a bundle to be banded directly above said movable member, said cutting means being spaced laterally from the portion of said supporting means that is adapted to support said bundle.

22. A machine of the class described comprising operable means to feed band material, means to support a bundle to be banded, operable means to join two portions of said band material together, operable means to sever said band ma-

5 terial between said joined portions and the remainder of said material, and mechanism operably connected to and adapted upon actuation to actuate said feeding means, joining means and severing means, said joining means embodying two die members operable relative to each other, said severing means embodying two independent cutting members operable relative to each other and spaced rearwardly of said die members and the portion of said bundle supporting means that is adapted to support a bundle, one of said cutting members extending higher than said latter mentioned portion, said feeding means embodying two feed rolls opposite each other and rearwardly of said cutting members.

JOHN DOUGLAS ROBERTSON.
